Application January 1, 1942, Serial No. 425,384

22 Claims. (Cl. 93—3)

This invention relates in general to a method of and machine for forming and filling packages, and attaching a thread, string, tape or the like thereto. More particularly, the invention contemplates the manufacture of a package, for example a tea bag, that comprises a commodity-holding portion or bag, a separable tag and a string or the like connected to the bag and to the tag.

A specific feature of the invention is a method of and mechanism for placing and sealing a string, tape or the like between strips or layers of sheet material.

One object of the invention is to provide a novel method and machine of the general character described for partially forming a package by the sealing together of two layers or strips of packaging material, such as paper, Cellophane, metallic foil, and the like, and filling, closing and attaching a string or the like to the package in rapidly successive steps and in one continuous operation.

Another object is to provide a novel and improved method and machine whereby a plurality of such packages shall be formed, filled and closed in a continuous series, said strips shall be sealed together in zones to form a commodity-receiving body portion or compartment for each package, certain of said zones between adjacent compartments shall be scored or weakened to form a tag integrally and separably connected to each package, a string or the like shall be secured in said certain zones so as to be connected to the body portion and to the tag for each package, and said packages shall be severed from each other, all in one continuous operation.

Another object is to provide novel means for sealing strips of material together with a string or the like between them.

A further object is to provide novel and improved means for feeding said strips of material in proper relation to said sealing means.

Further objects are to provide novel and improved means for depositing the substance to be packaged into the partially formed package; and to provide such depositing means that shall be adjustable in a novel and improved manner to vary the quantity of the substance deposited.

Additional objects of the invention are to provide novel and improved means for placing or inserting and securing or sealing a string or the like between, transversely of and at spaced points longitudinally of opposed strips of material that are fed step-by-step longitudinally; and to provide in such means, thread guides at one longi-

tudinal edge of such strips, mechanism for forming and pulling a loop of said thread with two reaches transversely of and between said strips from said longitudinal edge to a point beyond the other longitudinal edges of the strips, and means for severing said reaches at opposite sides of the bight of said loop between said mechanism and the second-mentioned edge of the strips.

Other objects, advantages and results of the invention will appear from the following description in conjunction with the accompanying drawings in which

Figure 1 is a front elevational view of the upper portion of a machine embodying my invention.

Figure 2 is a similar view of the lower portion of the machine below the line X—X of Figure 1, with the immaterial portions broken away.

Figure 3 is a fragmentary horizontal sectional view on the line 3—3 of Figure 2, portions being omitted for clearness in illustration.

Figure 4 is a horizontal sectional view on the line 4—4 of Figure 1.

Figure 5 is a transverse vertical sectional view on the line 5—5 of Figure 1.

Figure 6 is a top plan view of the machine with the cover in open position.

Figure 7 is a fragmentary horizontal sectional view on the line 7—7 of Figure 5.

Figure 8 is a composite side elevational and sectional view of the parts shown in Figure 7.

Figure 8a is a fragmentary horizontal sectional view on the line 8a—8a of Figure 8.

Figure 9 is an enlarged vertical sectional view on the line 9—9 of Figure 3.

Figure 10 is an enlarged composite horizontal sectional and plan view of the thread guiding and holding mechanism shown in Figures 3 and 9.

Figure 11 is a schematic front elevational view of the strip feeding mechanism, the sealing means and the substance depositing means, illustrating one step in the operation of the machine.

Figure 11a is a vertical sectional view on the line 11a—11a of Figure 11 with the addition of the thread holding and placing mechanism.

Figure 11b is a top plan view of the parts shown in Figure 11a.

Figures 11c and 11e are views similar to Figure 11a showing successive steps in the placing of the thread between the strips of packaging material.

Figures 11d and 11f are views similar to Figure

11b showing the parts as they are illustrated respectively in Figures 11c and 11e.

Figure 12 is a view similar to Figure 11 showing another step in the operation of the machine.

Figure 12a is a horizontal sectional view on the line 12a-12a of Figure 12.

Figure 13 is an enlarged fragmentary horizontal sectional view on the line 13-13 of Figure 11.

Figures 14 and 15 are similar views on the lines 14-14 and 15-15, respectively, of Figure 12.

Figure 16 is a fragmentary vertical sectional view on the line 16-16 of Figure 15.

Figure 17 is an enlarged vertical sectional view on the line 17-17 of Figure 5.

Figure 18 is an enlarged horizontal sectional view on the line 18-18 of Figure 17, and

Figure 19 is a perspective view of one type of package that can be formed according to my method and with my machine.

While my method and machine may be utilized for making many different packages, for the purpose of illustration I have shown the invention in conjunction with a known type of tea bag A (see Figure 19) which comprises two strips 1 and 2 of suitable tough, porous and water-resistant paper, said sheets being secured together at their margins adhesively and also preferably by interdigitation as indicated at 3, to form a bag-like container or commodity receiving body portion 4. One of the marginal portions serves as a tag, indicated at 5, and this tag is separable from the container portion 4 along a scored line or line of perforations 6. The tag 5 and the container portion 4 are connected by a string or the like 7 which has its ends secured between the sheets 1 and 2 in the marginal portions of the structure so that when the tag is separated from the container portion, the tag and string serve as a handle by which the container portion may be immersed in a cup or pot of hot water.

Describing my method and machine in their broader aspects, two strips 1 and 2 of the suitable packaging material are drawn step-by-step from supply rolls B into juxtaposition or side-by-side relation by a feeding mechanism C.

At the end of each step of movement the two strips 1 and 2 are sealed together by sealing mechanism D along their longitudinal edges and transversely, to form a bag-like receptacle having its mouth facing upwardly between the strips and to simultaneously close the open end of the next preceding container that was formed at the end of the immediately preceding step of movement. In the interval between the steps of movement and prior to the partial formation of each package above described, the substance or article to be packaged is deposited by a filling mechanism E into the mouth of the preceding package; and immediately after the deposit of the substance, a string is inserted or placed between the strips above the open end of the package by a mechanism that includes a thread holding and guiding mechanism I and a thread pulling mechanism K.

The feeding mechanism C draws from the roll B at each step predetermined quantities of the strips 1 and 2 required to form a single package, and an auxiliary feeding mechanism F constantly exerts tension on the strip so as to draw said quantities of the strips downwardly into proper position relative to the sealing means D, and at the same time moves the package strip or chain of packages downwardly to a severing mechanism G which successively separates the packages from

each other or from the strip. Approximately simultaneously with or slightly prior to the severing of the packages from the strip, the sealed zone 3 between two adjacent packages is operated upon by a suitable mechanism H, such as a branding mechanism, to form the scored line or line of perforations 6.

More specifically describing the invention, the machine includes a frame or casing L upon the front of which the strip feeding mechanism C is mounted. This mechanism includes a frame 8 on which are mounted two fixed guide bars 9 under which the respective strips 1 and 2 pass from the supply rolls B, and other idler rollers 10, one between each bar 9 and a pair of guide rollers 11.

A yoke 12 is mounted on a vertically reciprocable shaft 13 and has a strip pulling roller 14 disposed between the guide bars 9 and idler rollers 10 at each side of the frame 8. Each strip of packaging material is led from the corresponding supply roll under the corresponding bar 9 over the corresponding pulling roller 14, under the corresponding idler roller 10 and downwardly over the corresponding guide roller 11, the two strips being thus brought into juxtaposition or opposed side-by-side relation to each other and guided toward the sealing means D.

Between the rollers 10 and 11 are soft non-rotatable bars 15, each journaled on a yoke 16 that is in turn pivotally mounted on the frame 8 at 17 and has an arm 18 normally influenced by a spring 19 so as to press the corresponding brake bar 15 toward a brake platen 20 that is fixedly mounted on the frame 8 so as to positively clamp the corresponding strip 1 or 2 between the roller and the platen and hold the strip against longitudinal movement. Each yoke 16 also has an arm 21 which is underlaid by a finger 22 that is mounted on a vertically reciprocable rod 23.

The shaft 13 on which the yoke 12 is mounted is reciprocable in guides 24 in the frame of the machine and is held against rotation by a guide arm 25 that is slidably fit in a guide block 26 mounted on the frame. The shaft 13 is reciprocated by a lever 27 that is pivotally mounted on the shaft 28 in the frame and has a pin and slot connection 29 at one end with the shaft 13 and carries a roller 30 at its other end which follows a cam 31 on the drive shaft 32 of the machine, which is connected to any suitable source of power such as an electric motor.

The rod 23 that carries the finger 22 is reciprocated by a lever 33 which is pivotally mounted on a shaft 34 on the frame and has one end underlying and abutting the end of the rod and its other end provided with a roller 35 that follows a cam 36 on the drive shaft 32.

In operation of the machine so far described, periodically the strips 1 and 2 are held against longitudinal movement by the brake bars 15 as shown in Figure 11, when the yoke 12 is at the lower limit of its stroke and during upward movement of the yoke into the position shown by dot and dash lines in Figure 11 so that a predetermined length of each strip required to form a package is withdrawn from the corresponding roller B. Suitable brakes or drags 37 may be provided to prevent overrunning of the rolls. Then the rod 23 is actuated upwardly so that the finger 22 will swing the brake roller yokes 16 upwardly against the influence of the springs 19 to disengage the brake rollers 15 from the corresponding strips as shown by solid lines in Figure 11, after which the yoke 12 is lowered and simultaneously the auxiliary feeding means F draws

the strips 1 and 2 downwardly through the sealing mechanism D as shown by solid lines in Figure 11.

The sealing mechanism includes two sealing jaws 38 that are mounted to reciprocate toward and from each other in a horizontal plane and are guided in accurate alignment with each other during their movements by guide rods 39 each of which is fixedly mounted in one of the jaws and is slidably in openings in the other jaw. Each jaw is carried by an arm 40 which is rotatably mounted on a vertical shaft 41 secured in the frame L, the arm being pivotally connected to the jaw at 42. These arms 40 are simultaneously oscillated to move the jaws alternately toward and from each other by the respective crank arms 43 connected by links 44 to a slide 45 that has slots 46 and 47 which slidably engage the respective guide blocks 48 and 49. The slide carries a roller 50 that follows a cam groove 51 in a disc 52 which is keyed on the main drive shaft 32.

The two jaws 38 are substantially identical in construction and each includes a body portion 53 on which is mounted a crimping and sealing block 54. Preferably one of these blocks is movable toward and away from the corresponding body portion, and springs 55 are provided to yieldingly resist movement of the sealing block toward the body portion under the pressure exerted during the sealing operation on the packaging strips.

Each sealing block has a recess 56 in its face which is surrounded on three sides by a rim 57 having suitable corrugations or serrations. Where the package is to be approximately rectangular in shape as shown, the rim and corrugations are arranged in a manner corresponding to three sides of the rectangular package as shown in Figures 5 and 11a.

In the present instance, the package has the packaging material crimped and sealed along the four edges of the package, and each sealing block has two vertically disposed parallel series of corrugations 560 to grip the longitudinal edges of the packaging strips 1 and 2, and horizontal series of corrugations 561 to grip the packaging material strips transversely. The length of the series 560 is somewhat greater than the corresponding sides of the package to be formed, and below the transverse series 561 is a pair of short series of corrugations 562 to supplement the series 560 and form round corners on the commodity receiving compartment 4 of the package at the juncture of the transverse series 561 and the vertical series 560. The transverse series 561 is of a width corresponding to the width of the bottom edge of one package and the top edge and tag portion 5 of the next preceding package.

In forming the packages, the sealing blocks 54 are first separated as shown in Figures 3 and 11 and the packaging strips are pulled downwardly into juxtaposition between the sealing blocks. Thereupon, the sealing blocks are moved toward each other by the arms 40, 43 so as to cause the corrugations 560 and 561 to press the strips together and partially form a package to produce a bag-like structure having its upper end open between the strips at the upper ends of the sealing blocks, and simultaneously close the open end of the next preceding package. Where the strips 1 and 2 are of thermoplastic material or have a thermoplastic coating on their 75

adjacent sides, the sealing blocks 54 will have suitable electric heaters 58 (well known in the art) for heating the blocks to soften or fuse the thermoplastic material and seal the strips together. Where the edges of the strips are provided with ordinary adhesive, the heaters may be omitted.

After the strips have been sealed as above described, the sealing blocks are separated by oscillation of the arms 40 and the portions of the packaging strips that will have been supplied by the feeding mechanism C for the next package will be pulled downwardly by the auxiliary feeding means F preparatory to the partial formation of the next package. Then the spout 59 of the filling mechanism E (hereinafter described) is quickly lowered into the open end of the partially completed package to deposit the material to be packaged as shown in Figures 11 and 11a. As the spout 59 is raised or withdrawn, the string 7 is placed or inserted between the strips so as to be sealed therebetween as the open end of the package is closed.

The string guiding and holding mechanism I 25 and the string pulling mechanism K are shown as located at opposite longitudinal edges of the strips 1 and 2, and in juxtaposition to the portions 561 of the sealing blocks 54 so as to place the string approximately in the vertical plane at 30 which the faces of the sealing blocks meet during a sealing operation.

The thread guiding and holding mechanism is shown as including a horizontal bar 60 that is mounted on bracket arms 61 secured to the front 35 of the frame L. Upon this bar is mounted a block 62 on which is pivotally mounted on a horizontal axis as at 63 a thread guide 64 that has a vertical opening 65 communicating with a horizontal groove 66 in the top of the guide with 40 which in turn communicates a downwardly inclined opening 67. The thread or string is threaded upwardly through the opening 65 along the groove 66 and downwardly through the opening 67 as shown in Figure 9, and preferably 45 a tensioning lever 68 is pivoted on the thread guide and has a finger 70 to lie upon the thread in the groove 66. The block 62 has a vertical surface 71 which is normally overhung by the 50 portion of the thread guide 64 that carries the opening 67 so that a portion of the thread will depend from the thread guide 64 and along said surface 71, there being a space between the surface 71 and the overhanging portion of the thread guide which is traversed by the thread 55 so that the latter can be easily gripped. A thread holder cooperates with the surface 71 to periodically grip a portion of the thread therebetween and prevent longitudinal movement of the thread so that when the portion of the thread between 60 said surface 71 and thread guide is gripped and pulled, the thread will be withdrawn from the supply and formed into a loop having two approximately parallel reaches. This thread holder comprises a head 72 mounted on a body portion 73 that is pivotally connected at 74 to the block 62, so that the head 72 may swing toward and away from the surface 71, as shown in Figure 10. Preferably the head 72 has a lip 75 to prevent the thread from being pulled in the plane of the surface 71 from between the head and said surface when they are in thread-holding relation to each other.

As shown, the thread holder is actuated by one of the sealing jaws 38 through a connecting

rod 76 that has a notch 77 pivotally connected to a pin 78 on the body portion of the thread holder, and its other end frictionally slidably in said sealing jaw. The rod 76 is slidably mounted in an opening 79 in said jaw and the jaw has a recess 80 communicating with said opening 79 in which is mounted a friction block 81 that is forced and held in contact with the rod 76 by a spring 82.

Normally, when the sealing jaws are in their open position, the end of the rod 76 opposite the thread holder abuts an adjustable stop screw 83 that is mounted in an arm 84 on the bar 80, so that the head 72 of the thread holder is swung away from the surface 71 of the block 62, as shown by solid lines in Figure 10. As the sealing jaws begin to move toward their closed positions, the bar 76 moves with its corresponding jaw so as to clamp the thread or string M between the head of the holder and the surface 71 as shown by dotted lines in Figure 10, and upon return of the jaws to their open position the rod 76 moves with its jaw so as to actuate the thread holder to release the string. Upon further opening of the jaws the rod engages the stop screw 83 and the jaw continues to move relatively to the rod to its normal open position.

While the thread or string is held by the thread holder, the portion of the string between the surface 71 and the opening 67 of the thread guide is gripped by the hook 85 of the thread pulling mechanism K which forms and pulls a loop of the thread transversely of and between the packaging sheets as shown in Figures 11a to 11f inclusive. The hook has a shank 86 that is slidably in a guide tube 87 secured in the frame L of the machine, and the shank is reciprocated by a lever 88 that is journaled on the shaft 28 and has a pin and slot connection 89 at one end with the shank 86 of the hook. The other end of the lever carries a roller 90 that follows a cam 91. A tension spring 92 is connected between the lever 88 and the frame of the machine so as to maintain the follower roller 90 in snug contact with the cam 91 and insure proper actuation of the hook. The cam is so shaped that it in conjunction with the spring 92 and roller 90, will quickly project the hook from its normal position shown in Figure 5 transversely of the strips to hook the string, and will then quickly retract the hook to form the loop and pull the string transversely of the packaging strips.

Preferably the portions 861 of the sealing blocks have grooves 93 to provide a clearance for the reaches of the loop of the string when the packaging strips are sealed together with the string 55 between them.

The hook is operated in the interval between the steps of feeding movement of the packaging strips and immediately following the deposit of the substance to be packaged in the open mouth of the partially formed package and during closing movement of the jaws. As the spout 59 of the filling mechanism E begins to retract after the filling operation, as shown in Figures 11a and 11b, the hook is projected transversely of and between the packaging strips as shown in Figures 11c and 11d, and is immediately retracted to pull the loop Y of thread transversely of and between the packaging strips in juxtaposition to the zones of the strips that are to be sealed together to 70 close the filled package and partially form the next succeeding package. Preferably the loop is pulled so that its bight is carried beyond the longitudinal edge of the strips opposite the thread guides 67 and 71, 72, as shown in Figures 11e and 75

11f. Then as the sealing blocks are next brought together as shown in Figure 12, the reaches of the loop are sealed between the strips and are severed from each other at opposite sides of the bight between the hook and the adjacent longitudinal edge of the strips as shown in Figures 12a and 15.

For severing the reaches of the string, a knife blade 94 is rigidly mounted on one of the sealing jaws and another blade 95 is pivotally mounted at 96 on the other jaw and is normally influenced by a spring 97 to bring the edge of the blade 95 into proper shearing relation to the edge of the knife 94. The blade 94 has a tail 98 that slidably 15 engages the blade 95 to insure proper shearing relation of the two blades as the sealing jaws are brought together.

Simultaneously with each sealing operation, a previously formed package is severed from the package strip or series of packages by the severing mechanism G which comprises cutting blades 99 and 100 which generally are the same in structure and operation as the blades 94 and 95. The package strip is severed in one of the transverse zones between the adjacent packages and intermediate the reaches of the string.

Simultaneously with the severing of each package from the package strip, said package is subjected to an operation to form the scored line or line of perforations 6 between one of the reaches of string and the adjacent commodity holding body portion or compartment 4. As shown, this means comprises a branding die 101 that is preferably mounted on one of the sealing jaws and cooperates with a platen 102 on the other sealing jaw, the die and platen gripping between them the sealed package strips as the sealing jaws are brought together for the sealing operation. Preferably the branding die 101 is mounted to yield relatively to the platen during the branding operation.

In addition to forming the line of perforations 6, the branding die may be formed to produce branded inscriptions on the tag portion 5 of each package.

It is desirable that the bight portions of the thread loops be conveyed away as they are severed, and for this purpose I may provide a suction pipe 103 connected to any suitable suction pump and having its inlet 104 juxtaposed to the hook 85 when the latter is in its normal position, whereby suction will draw the bit of string off the hook and to a suitable receptacle.

As hereinbefore described, the package strip is constantly pulled downwardly to advance the strip as the packages are formed in succession, by the auxiliary feeding means F which is shown as including a pair of rotatable cylindrical brushes 105 which receive the package strip between them, the bristles yieldingly and frictionally exerting pressure on opposite sides of the strip so that as the brushes are rotated in the direction indicated by arrows, the package will be placed under tension and pulled downwardly.

The rollers are mounted in an auxiliary casing 106 on shafts 107 which are geared together by pinions 108. One of the shafts has a second pinion 109 that meshes with a gear 110 on the countershaft 111 on which is a beveled pinion 112 that meshes with a beveled gear 113 that is keyed on a countershaft 114 which may be connected to the source of power in any suitable manner, whereby the rollers are continuously driven during operation of the machine.

Suitable guides 115 and 116 may be provided for guiding the package strip in a straight path between the brushes and for preventing the package strip from being wound around the brushes.

Any suitable mechanism may be provided for actuating the spout 59 of the filling mechanism E, but as shown the spout 59 is telescopically reciprocable upon an outlet tube 117 into which predetermined quantities of the substance to be packaged are ejected from a hopper 118 by a measuring and dispensing mechanism generally designated 119. For reciprocating the spout, I may utilize a vertically reciprocable shaft 120 mounted in the frame L of the machine and connected by an arm 121 to the spout. The shaft 120 is pivotally connected by links 122 to one arm of a bell crank lever 123 which is journaled on a horizontal shaft 124 mounted in the frame of the machine. The other arm of the bell crank lever 123 has a follower roller 125 that engages a cam 126 on the drive shaft 32, whereby the lever 123 will be oscillated to lower and raise the spout 59 in timed relation to the steps of feeding of the packaging strips.

The measuring and dispensing mechanism 119 includes a casing in which is rotatable a drum 127 keyed on a horizontal tubular shaft 128 which is journaled in bearings 129 and 130 in the machine frame. The drum 127 has a flange 131 over which is telescopically slidably the flange 132 of another drum 133 that is coaxially slideable on the shaft 128. The drum 127 has a plurality of circumferentially spaced notches 134 in its flange that open both longitudinally and radially of the drum and successively communicate with the hopper 118 as the drum is rotated, and the flange 132 of the drum 133 has a finger 135 movable in each of the notches 134 to vary the capacity thereof, said fingers 135 forming portions of the side walls for the respective notches 134 so as to provide measuring pockets opening radially through the peripheries of the drums.

For adjusting the drum 133 to vary the capacity of said measuring pockets, a nut 136 is threaded on the shaft 128 and is rotatable but longitudinally non-movable relatively to the hub of the drum 133, so that rotation of the nut would cause axial movement of the drum on the shaft 128 and thereby move the fingers 135 into or out of the notches 134. A lock nut 137 is threaded on the shaft 128 to hold the drum in adjusted position.

For rotating the drums simultaneously, a beveled pinion 138 is rotatably mounted on the shaft 128 and meshes with a beveled pinion 139 on a countershaft 140 that is actuated by a Geneva drive 141 from the drive shaft 32, so that the shaft 128 will be rotated step-by-step in timed relation to the feeding of the packaging strips to empty the contents of one of the pockets 134 into the discharge spout 59 at each step of movement and simultaneously bring one of the pockets into communication with the hopper 118 for filling. The beveled pinion 138 is connected to the shaft 128 through a novel clutch mechanism which includes a collar 142 keyed on the hub of the pinion 138 and having V-shaped notches 143 in one edge to receive corresponding shaped teeth on a sleeve 144 that is freely rotatable on the hub of the beveled pinion 138 and has angular notches 145 in one edge which cooperate with correspondingly shaped teeth 146 on a clutch member 147 that is keyed on the

shaft 128 and movable longitudinally thereof to engage and disengage the teeth 146 with and from the notches 145. As shown, the clutch member 147 is operated by a pull rod 148 that is longitudinally slidably mounted within the tubular shaft 128 and has a knob 149 at the front of the machine. The collar 142 is normally influenced into engagement of the sleeve 144 by a compression spring 150 and longitudinally sliding movement of the collar 142 and sleeve 144 on the hub of the beveled pinion 138 is limited by a stop plate 151 secured to the end of said hub.

With this construction, in normal operation, the clutch member 147 will be disconnected from the sleeve 144 and the beveled pinion 138 will freely rotate on the shaft 128 without driving the measuring and dispensing mechanism 119. By pulling on the knob 149, the clutch member 147 is brought into engagement with the sleeve 144 which is yieldingly held in engagement with the collar 142 by the springs 150, and thus the shaft 128 and measuring and dispensing drums 127 and 133 will be rotated. Should rotation of said drums be interrupted, as by jamming of a solid object in one of the pockets 134 between the drums and the walls of the hopper, the V-shaped teeth on the sleeve 144 will slip out of the notches 143 in the collar 142 and relieve the shaft 128 of the driving force imposed by the driving mechanism 32, 141, 138, 139.

For releasably holding the clutch member 147 in its engaged and disengaged positions, the shaft 128 may have sockets 152 to be engaged by a spring pressed ball detent 153.

While I have shown and described my invention as embodied in certain details of structure, it should be understood that this is primarily for the purpose of illustrating the principles of the invention, and that many modifications and changes may be made in the details of structure without departing from the spirit or scope of the invention. It will also be understood by those skilled in the art that the shapes of the cam surfaces may be modified and changed if desired to vary the time and relation of the operation of the various strip feeding mechanism C, sealing mechanism B, filling mechanism E, string inserting mechanism, etc. Moreover, the various shafts may be connected to any suitable sources of power in any suitable way.

Having thus described my invention, what I claim is:

1. In a method of forming, filling and attaching a string to packages, which comprises feeding two continuous strips of packaging material into juxtaposition step-by-step, securing said strips together simultaneously along their longitudinal margins and in transverse zones of the strips at the end of each step of movement to form a bag-like container having an open end and simultaneously closing the open end of the next preceding bag-like container that was formed during the preceding step of feeding of said strips and depositing a substance to be packaged through said open end of each container prior to the sealing together of said strips to close said open end of the container, the additional steps of guiding a string to a point at one longitudinal edge of said strips, pulling a portion of said string transversely of and inwardly between said strips in each said transverse zone at the end of each step of movement of the strips and prior to the securing of the strips together in said zones so that said string will be secured between said

strips when they are secured together in said transverse zone.

2. The steps in the method of forming filling and attaching a string to packages, consisting in feeding two continuous strips of packaging material into juxtaposition step-by-step, securing said strips together simultaneously along their longitudinal margins and in transverse zones of the strips at the end of each step of movement to form a bag-like container having an open end and to simultaneously close the open end of the next preceding bag-like container that was formed during the preceding step of feeding of said strips, guiding a string to a point spaced from said strips and outwardly beyond one longitudinal edge thereof, forming and pulling a loop of said string transversely of and inwardly between said strips to form two reaches of string in each said transverse zone prior to the securing of the strips together whereby said string will be secured between said strips when they are secured together in said transverse zones.

3. The method of forming, filling and attaching a string to packages, consisting in feeding a plurality of continuous layers of packaging material into juxtaposition with a step-by-step movement, successively at the end of each step of feeding of said layers securing said layers together to form a bag-like container having an open end and depositing substance to be packaged into said container through said open end, closing said open end at the end of the next step of feeding of said strips whereby to form a chain of closed containers, guiding a string to a point at one longitudinal edge of said strips, pulling said string transversely of and between said strips toward the other edge of the strips and across said open end of each container prior to the closing of said open end, and securing said string to said container as said open end is closed.

4. A packaging machine including means for guiding a plurality of continuous strips of packaging material into juxtaposition, a sealing mechanism comprising a pair of opposed sealing blocks movable toward and from each other and having portions to successively grip said strips between them for securing said strips together simultaneously along their longitudinal margins and transversely to form a bag-like container having an open end and thereafter release the strips, means for depositing substance to be packaged into said container through said open end after release of the strips by said blocks, means for moving said strips between said blocks after said substance has been deposited in said container and while said strips are released, said sealing blocks having other portions to grip and secure said strips together transversely at said open end of the container to close the latter as said blocks next move toward each other and grip the strips between them to form another bag-like container, means for guiding a string to a point at one longitudinal edge of said strips in juxtaposition to the last-mentioned portions of said sealing blocks, and means for pulling a portion of said string transversely of and between said strips and toward the other longitudinal edge thereof while said strips are released, whereby said portion of the string will be secured between said strips when the latter are secured together transversely.

5. A packaging machine including means for guiding a plurality of continuous strips of packaging material into juxtaposition, a sealing mechanism comprising a pair of opposed sealing blocks

movable toward and from each other and having portions to successively grip said strips between them for securing said strips together simultaneously along their longitudinal margins and transversely to form a bag-like container having an open end and thereafter release the strips, means for depositing substance to be packaged into said container through said open end after release of the strips by said blocks, means for moving said strips between said blocks after said substance has been deposited in said container and while said strips are released, said sealing blocks having other portions to grip and secure said strips together transversely at said open end of the container to close the latter as said blocks next move toward each other and grip the strips between them to form another bag-like container, means for guiding a string to a point spaced from said strips and outwardly of one longitudinal edge thereof in juxtaposition to the last-mentioned portions of said sealing blocks, and means for forming and pulling a loop of said string transversely of and inwardly between said strips to form two reaches of string along each transverse zone before said strips are sealed together thereat whereby said reaches of string will be sealed between said strips when said strips are sealed along said transverse zones, and means for depositing a substance to be packaged through said open end of each compartment prior to the closing of said open end.

6. The packaging machine set forth in claim 5 with the addition of means for severing said reaches of string adjacent the bight of the loop from each other at the other longitudinal edge of said strip.

7. In a packaging machine, the combination with means for feeding two continuous strips of packaging material into juxtaposition step-by-step, and means operable at the end of each step of movement for sealing said strips together simultaneously along longitudinally and transverse zones to form a bag-like compartment having an open end and simultaneously close said open end of the next preceding compartment that was formed during the next preceding step of feeding of said strips: of means for guiding a string to a point at one longitudinal edge of said strips, means for pulling a portion of said string transversely of and between said strips in the intervals between the steps of movement whereby said portions of the string will be sealed between said strips when they are sealed together, and means for depositing a substance to be packaged through said open end of each compartment prior to the closing of said open end.

8. A packaging machine comprising means for feeding two continuous strips of packaging material into juxtaposition step-by-step, means operable at the end of each step of movement for sealing said strips together simultaneously along longitudinal and transverse zones of the strip to form a bag-like compartment having an open end and simultaneously close said open end of the next preceding compartment that was formed during the next preceding step of feeding of said strips, means for guiding a string to a point spaced from said strips and outwardly of one longitudinal edge thereof, means for forming and pulling a loop of said string transversely of and inwardly between said strips to form two reaches of string along each transverse zone before said strips are sealed together thereat whereby said reaches of string will be sealed between said strips when said strips are sealed along said transverse zones, and means for depositing a substance to be packaged through said open end of each compartment prior to the closing of said open end.

9. The packaging machine set forth in claim 7 with the addition of means for scoring said strips along each transverse zone between said string and the closed compartment to form a tag for each package.

10. The packaging machine set forth in claim 8 with the addition of means for scoring said strips along each transverse zone between one of said reaches of string and the closed compartment to form a tag for each package, and means for severing said reaches of string from each other at the other longitudinal edge of said strips.

11. The packaging machine set forth in claim 8 with the addition of means for scoring said strips along each transverse zone between one of said reaches of string and the closed compartment to form a tag for each package, means for severing said reaches of string from each other at the other longitudinal edge of said strips, and means for severing said strips along each transverse zone between said tag of one package and the adjacent end of the next succeeding package to separate said packages from each other.

12. The steps in a method of making a package with a string-attached tag, consisting in feeding two strips of material into juxtaposition step-by-step, sealing said two strips together at the end of one step of movement to form a bag-like compartment having an open end, depositing a commodity in said compartment, placing a loop of string having two approximately parallel reaches between said strips outwardly of said open end in the interval between steps of movement and with the bight of said loop projecting from the edge of said strip, sealing said strips together at the end of the next step of movement to close said open end and seal said reaches of string between said strips, scoring said strips between one reach and the adjacent closed compartment to form a tag for each package, severing said reaches from each other at said edge of the strips at opposite sides of said bight, and severing said strips between said reaches to separate said packages from each other.

13. A packaging machine comprising means for feeding and sealing together step-by-step opposed layers of packaging material along longitudinally extending and transversely extending zones to form a series of commodity containing compartments, means for depositing commodities in each compartment prior to closing thereof, means for guiding a thread to a point at one longitudinal edge of said layers, a hook movable transversely of and between said layers for pulling a portion of said thread from the first-mentioned to the second-mentioned edge of said layers between the layers prior to sealing thereof, and means for actuating said hook in the interval between steps of movement of said layers whereby said portion of said string will be sealed between said layers as the latter are sealed together.

14. A packaging machine comprising means for feeding and sealing together step-by-step opposed layers of packaging material along longitudinally extending and transversely extending zones to form a series of commodity containing compartments, means for depositing commodities in each compartment prior to closing thereof, thread guides spaced along one longitudinal edge of said layers, a hook movable transversely of and between said layers to engage said thread between said guides and form and pull a loop of said thread with two reaches from the first-mentioned edge to the second-mentioned edge of said layers prior to sealing of the strips, and

means for actuating said hook in the interval between steps of movement of said layers whereby said portion of said string will be sealed between said layers as the latter are sealed together.

15. Means for sealing a thread between strips of material, comprising means for feeding strips of material into opposed relation step-by-step, means for sealing said strips together at the end of each step of movement, a thread guide adjacent one longitudinal edge of said strips, a hook normally located adjacent the other longitudinal edge of said strips and reciprocable transversely of and between said strips prior to sealing thereof to engage said thread and pull it transversely between said strips, and means for actuating said hook in the intervals between steps of movement of said strips, whereby said thread will be sealed between said strips as the latter are sealed together.

16. Means for sealing a thread between strips of material, comprising means for feeding strips of material into opposed relation step-by-step, means for sealing said strips together at the end of each step of movement, thread guides spaced along one longitudinal edge of said strips, a hook normally located adjacent the other longitudinal edge of said strips and reciprocable transversely of and between said strips before they are sealed to engage a thread between said guides and form and pull a loop of thread with two reaches between said strips from the first-mentioned edge with the bight of the loop projecting beyond the other edge thereof, means for actuating said hook during the intervals between said steps of movement of said strips, and means for severing said reaches of thread from each other at opposite sides of said bight between said hook and the second-mentioned edge of said strips, whereby said reaches of string will be sealed between said strips as the latter are sealed together and each reach will be connected to another reach by a portion of said thread that extends along the first-mentioned edge of said strips.

17. A packaging machine comprising means for feeding strips of packaging material into opposed spaced relation and moving said strips longitudinally step-by-step, means operable at the end of each step of movement for sealing said strips together along longitudinal zones and transverse zones at the same time to form a bag-like compartment having an open end and simultaneously close the open end of the next preceding compartment so that said transverse zones shall be of a length suitable to form tags for packages which include the respective compartments, thread guides spaced along one longitudinal edge of said strips, a hook normally located adjacent the other longitudinal edge of the strips and reciprocable between said strips along said transverse zones before sealing of the strips thereat so that the hook will engage said thread between said guides and form and pull a loop of the thread having two reaches between said strips to locate the bight of the loop beyond the second-mentioned edge of the strips, whereby said reaches of thread will be sealed between said strips when the latter are sealed together, means for severing said reaches between said hook and said second-mentioned edge of the strips so as to leave the bight portion of the loop in said hook, means for scoring said strips along each transverse zone between one of said reaches and the adjacent closed compartment, and means for severing said

strips along each transverse zone between the other reach of thread and the next succeeding compartment to separate the packages from each other, whereby each package has one reach of thread in its tag and another reach at its other end and said reaches are integrally connected together by another portion of said thread.

18. The method of making a package with a string-attached tag which comprises feeding two strips of material into juxtaposition step-by-step, sealing said two strips together at the end of one step of movement to form a bag-like compartment having an open end, and depositing a commodity in said compartment, characterized by the steps of guiding a string at two points spaced longitudinally of one edge of said strips, periodically holding said string at one of said points against longitudinal movement, forming a loop of said string between said points and while the string is so held pulling said loop transversely of and between said strips in the interval between steps of movement of said strips and sealing said strips together to close said open end and seal said loop of string between said strips.

19. Mechanism for sealing a thread between strips of material, comprising means for feeding strips of material into opposed relation step-by-step, means for sealing said strips together at the end of each step of movement, thread guides spaced along one longitudinal edge of said strips, a hook normally located adjacent the other longitudinal edge of said strips and reciprocable transversely of and between said strips before they are sealed to engage a thread between said guides and form and pull a loop of thread with two reaches between said strips from the first-mentioned edge with the bight of the loop projecting beyond the other edge thereof, means for holding said thread at the guide that is remote from the thread supply against longitudinal movement during the intervals between said steps of movement, and means for actuating said hook while said string is so held, whereby said reaches of thread will be sealed between said strips as the latter are sealed together.

20. Mechanism for sealing a thread between strips of material, comprising means for feeding strips of material into opposed relation step-by-step, means for sealing said strips together at the end of each step of movement, comprising two jaws movable toward and from each other successively to grip and release said strips between them, thread guides spaced along one longitudinal edge of said strips, a hook normally located adjacent the other longitudinal edge of said strips and reciprocable transversely of and

between said strips before they are sealed to engage a thread between said guides and form and pull a loop of thread with two reaches between said strips, one of said thread guides including a clamping surface and a holder movable toward and from said surface successively to grip and release said thread between them, means actuating said holder upon the beginning of movement of said jaws toward each other at the end of each step of movement of said strips so as momentarily to grip and hold said thread against longitudinal movement and thereafter release said thread, and means for actuating said hook while the string is so held, whereby said reaches of thread will be sealed between said strips as the latter are sealed together.

21. Mechanism for sealing a thread between strips of material, comprising means for feeding strips of material longitudinally in opposed spaced relation, means for sealing said strips together, and means for inserting a thread between said strips prior to sealing thereof comprising thread guides spaced along one longitudinal edge of said strips, one of said guides including a clamping surface and a holder movable toward and from said surface to grip and release successively said thread between them, means actuating said holder to momentarily grip and hold said thread and thereafter release it, a device movable transversely of and between said strips at a point ahead of said sealing means to engage a thread between said guides and pull said thread transversely of and between said strips before they are sealed, and means for actuating said device while said thread is gripped by said holder, whereby said thread will be sealed between said strips as the latter are sealed together.

22. The steps in a method of making a package with a string-attached tag, consisting in feeding two strips of material into juxtaposition, sealing said two strips together to form a bag-like compartment having an open end, depositing a commodity in said compartment, guiding a string at two points spaced longitudinally of one edge of said strips, periodically holding said string against longitudinal movement at one of said points nearer said compartment, forming a loop of said string between said guides and while the string is so held pulling said loop transversely of and between said strips adjacent said open end of said compartment and sealing said strips together to close said open end and seal said loop of string between said strips.
